[57] CLAIM

The ornamental design for a digital engine analyzer, substantially as shown.

DESCRIPTION

FIG. 1 is a right front perspective view of a digital engine analyzer showing my new design;

FIG. 2 is a front elevational view thereof;

FIG. 3 is a right side elevational view thereof, the left side being a mirror image thereto;

FIG. 4 is a top plan view thereof;

FIG. 5 is a bottom plan view thereof;

FIG. 6 is a rear elevational view thereof; and

FIG. 7 is a front perspective view thereof in the raised position.

*Fig. 1.**Fig. 2.**Fig. 3.**Fig. 4.**Fig. 5.**Fig. 6.**Fig. 7.*
